UNITED STATES PATENT OFFICE.

MOSES D. GREENGARD AND FRADELSHON HARRIS, OF ST. LOUIS, MISSOURI.

FARE-COLLECTOR.

SPECIFICATION forming part of Letters Patent No. 444,882, dated January 20, 1891.

Application filed March 15, 1890. Serial No. 344,064. (No model.)

To all whom it may concern:

Be it known that we, MOSES D. GREENGARD and FRADELSHON HARRIS, residing in the city of St. Louis and State of Missouri, have invented certain new and useful Improvements in Fare-Collectors, of which the following is a specification.

Our invention, which is in the nature of a portable fare-collector for street and railway cars, has for its object to provide a device which may be conveniently carried by the conductor and presented to each passenger to deposit the fare, the construction being such as to prevent the possibility of extracting same after it has been deposited by the passenger, or in any manner tampering with the same without being detected.

To this end our invention consists of a casing or receiver constructed substantially in the manner hereinafter described, provided with suitable interior mechanism arranged and combined therewith for the purpose and in the manner hereinafter specifically set forth in the annexed specification and particularly pointed out in the claims, reference being had to the accompanying drawings, in which—

Figure 1 is a perspective view of our improved collector. Fig. 2 is a vertical section of the same on the line 2 2, Fig. 1. Fig. 3 is a similar view on the line 3 3, Fig. 1; and Fig. 4 is a detail view illustrating the means for operating the gong.

In the accompanying drawings the collector A is shown formed with a receiving-chamber a, having a funnel-shaped mouth a', provided with a contracted end a'', a fare-arresting circular casing A', disposed at the lower end of the receiving-chamber a, and a cash box or receptacle A² below the casing A'. The receiving-chamber is provided with a transpicious front face, as shown at 1, whereby the conductor and the passenger can see the fare when it is held at the bottom of the said chamber, and with the usual deflector-plates 2 2, as shown.

B B denote rings secured to the sides of the casing a, which serve as a convenient means for securing the collector to the ends of a strap b, adapted to be supported over the shoulders of the conductor or from any other suitable place.

C indicates a circular disk or wheel eccentrically journaled inside the casing A', one face thereof adapted to operate adjacent the wall a³ of said casing, a fare-passage 3 being provided between the front peripheral face of said disk and the front wall 4 of the casing A'.

The fare-arresters D D consist of blades arranged at right angles to each other, which pass through similarly-arranged apertures d d in the disk C, such blades having radial movements in relation to the said disk by means of the eccentric position of said disk within the casing, such blades forming radial valves 5 5, adapted to successively close the opening 6 6 between the receiving-chamber and the casing and hold the fare in sight until the disk is turned by the conductor to drop the fare into the box A². As it is necessary that in turning said disk the revolution thereof should be so adjusted that when one valve moves downward to discharge the fare the next succeeding valve shall take its previous position and close the opening 6, I provide the peripheral face of the disk with a series of notches E equal the number of blades and arranged in the same relation therewith, such notches having an inclined edge e and a straight edge e', so as to permit said wheel being turned in one direction, (see arrow,) but not in a reverse direction, a spring detent or pawl F, having beveled head f, being arranged to engage said notches E as they turn into position in a manner clearly understood by reference to Fig. 2 of the drawings. G denotes a knob extended to without the casing A', which is connected with the disk C and serves as a convenient means for turning said disk.

The spring-detent F is preferably disposed in a housing 10, formed on the rear face of the casing, in which is also mounted a gong H, provided with the usual spring-hammer h, the upper end of which normally is disposed in the path of projections J J of a number equal the notches formed on the disk C, which engage said hammer and operate to ring the gong at each quarter-turn of said disk.

The cash-receptacle A² is provided with a door 20, hinged at the lower end to the bottom of the case, provided with a suitable locking device at its upper end. If desired,

the door may be hinged to the lower face of the case at 30 and provided with a lock at 40, as shown in dotted lines, Fig. 2.

From the foregoing description, taken in connection with the drawings, the advantages and operation of our improved fare-collector will readily appear.

It will be seen that after the fare is deposited in the collector by the passenger the same will pass down over the deflectors and be held by valve 5, which projects under the opening 6. The conductor then gives the knob a quarter-turn, which allows the fare to be dropped into the box at the bottom, at the same time causing the gong to ring. It will also be observed that the relation of the disk C and the casing A' is such as to cause the blades to be reciprocated radially inward and outward in the apertures, so as to cause the ends thereof to be pushed in position at the proper intervals to close the opening 6.

By our construction it will be impossible to remove the fare by inverting the collector or otherwise than that of unlocking the cash-box.

It is obvious that in place of the knob G a lever may be employed to turn the disk C.

A suitable guard 50 is arranged over the glass front to prevent the same being accidentally broken.

Having thus described our invention, what we claim, and desire to secure by Letters Patent, is—

1. In a fare-collector, the combination, with the receiving-chamber a, the cash-box A², and the intermediate chamber A', of the disk C, journaled eccentrically in the said chamber A', one face of said disk arranged for contact with one wall of said chamber A', whereby a coin-passage between said disk and the opposite wall of chamber A' is formed, a series of valves radially adjustable in disk C, said disk formed with a series of notches and a series of projections, a stop-pawl, and a gong-operating device projected through the wall of the chamber A' adjacent the meeting end of said chamber and disk, adapted to engage, respectively, with the notches and projections on the disk, substantially as and for the purpose described.

2. In a fare-collector, the combination, with the receiving-chamber a, having a transplicuous side, the cash-box A², and the casing A' intermediate of the chamber a and the box A²

and communicating therewith, of the disk C, 55 journaled eccentrically in the said casing, a series of radially-movable blades operating through said disk and adapted to cut off communication between the chamber and box, a series of notches formed in the disk, a detent 60 adapted to engage said notches and hold said disk from movement in one direction, and means for rotating said disk, substantially as and for the purpose described.

3. In a fare-collector, the combination, with 65 the receiving-chamber a, the cash-box A², and the circular casing A', disposed intermediate of and communicating with said chamber and box, of the disk C, centrally journaled eccentrically of the circular casing A', the radially-adjustable blades operating through said disk, said blades adapted to close communication between the chamber a and box A² and to arrest the fare, a turning knob secured to said disk, a series of projections formed on said 75 disk of a number similar to the blades, and a gong having a spring-hammer adapted to normally project in the path of the movement of the projection, substantially as and for the purpose described.

4. The hereinbefore-described improved fare-collector, consisting of a receiving-chamber having a receiving-opening at its upper end, a transplicuous side, a series of deflectors arranged below the receiving-opening, a 85 circular casing A', arranged below said chamber, a cash-box secured to the lower edge of said casing, said box, chamber, and casing having open communication, the disk C, journaled eccentrically within said casing, provided with radially-adjustable blades operating in transverse apertures in the disk, said blades adapted to project to close the communication between said chamber a and box A², said disk provided with a series of notches 95 and a series of projections, a spring-detent adapted to engage said notches and hold the disk from movement in one direction, a gong having a spring-hammer, the free end thereof adapted to be engaged by the projections on 100 the disk when said disk is rotated, and means for rotating said disk, all arranged substantially as and for the purpose described.

MOSES D. GREENGARD.
FRADELSHON HARRIS.
